(57) CLAIM

The ornamental design for a handle for rolling luggage, as shown and described.

DESCRIPTION

FIG. 1 is a perspective view of the present invention;

FIG. 2 is a right side view of the present invention;

FIG. 3 is a side view of the present invention;

FIG. 4 is a top view of the present invention;

FIG. 5 is a bottom view of the present invention; and,

FIG. 6 is an additional perspective view of a second embodiment of the present invention.

The broken line showing in FIGS. 1–3, and of a piece of luggage in FIG. 6, is for illustrative purposes only and forms no part of the claimed design.
